JOHN S. BITNER, OF FORT WAYNE, INDIANA, ASSIGNOR TO WAYNE NOVELTY AND PUBLISHING COMPANY, OF FORT WAYNE, INDIANA, A CORPORATION OF INDIANA

FLAGSTAFF HOLDER

Application filed April 22, 1930. Serial No. 446,257.

This invention relates to improvements in flag staff holders such as is used for mounting a flag in supported relation with a fender or other part of an automobile so that the flag is displayed as a signal or decoration. The object of the invention is to provide an attachment applicable to the fender of an automobile for holding a flag staff, constructed in such manner that its various parts are permanently connected together whereby liability of disconnection or loss of such parts is obviated. Another object is to provide a construction whereby the device may be quickly applied and removed from operative position both in connection with a fender and with a flag staff.

An embodiment of the invention is illustrated in the accompanying drawings, in which:—

20 Fig. 1 is a side elevation of a holder in which the invention is embodied;

Fig. 2 is an elevation projected from Fig. 1 in a plane at right angles thereto.

The illustrative embodiment of the invention comprises a standard made of a single bar 1 of spring steel, shaped at its lower end to form a loop 2 with a contiguous upwardly extending end portion 3 having an inwardly extending indentation 4 adjacent the loop 3 and an outwardly extending indentation 5 above the former indentation, the upper end 6 of said portion constituting a jaw that is normally spaced from the main portion 7 of the bar and toward which the jaw is movable when pressure is applied to the upwardly extending end portion 3. The upper end of the bar 1 is shaped so as to form a loop 8 having a downwardly extending end portion 9 constituting a spring tongue.

40 A U-shaped yoke 10 is placed astride of the upturned end portion 3 of the bar as well as the main portion 7 thereof, and between the extending ends 11 of the yoke is disposed a lever 12 upon a pivot 13, which lever is provided with a cam 14 on its pivoted end. The closed end of the yoke 10 rests in the indentation 4 of the upturned portion 3 of the bar, and the cam 14 is so disposed with respect to the lever that when the lever is 45 turned upwardly the upturned portion 3 is

drawn toward the main portion 7 of the bar through the action of the yoke 10 and cam 14. In this manner the jaw 6 is moved to its closed or clamping position.

A cushion 15 is secured to the main portion 55 7 of the bar upon the face thereof adjacent the jaw 6, said cushion extending between the upturned portion 3 of the bar and the main portion 7 thereof. The lower end of said cushion projects downwardly into the 60 yoke 10, and its upper end is attached to the bar 1 by any suitable means such as a wire fastener 16.

The spring tongue 9 has permanently secured thereto a stud 16 that projects loosely 65 through the adjacent portion 17 of the bar 1, the outer end 18 of which stud is perforated so as to receive therein a flag staff 19. The stud 16 is secured to the top 9 in such suitable manner as to permit axial turning movement of the stud without having longitudinal movement in the tongue. The opening 20 in the portion 17 of the bar is encompassed by an inwardly extending collar 21 that is integral with the bar 1 and is formed for the purpose of reinforcing the bar about said opening. The bar has formed therein a transversely disposed rib 22 located at a point beneath the opening 20, which rib serves as a stop for the lower end of the flagstaff 19. 70 Also, the upper portion 17 of the bar above said opening has made therein a transversely disposed rib 23 provided with a series of notches 24 in which the flag staff may be selectively seated and therein held in various 75 adjusted positions when said staff is secured in the stud.

The bar 1 is bent at a point between its end looped portions to the extent of one quarter of a turn as indicated by 25 so that the upper 80 portion 17 of the bar extends in a vertical plane at right angles to that of the main portion 7 thereof. Thus, the tilting adjustment of the flag staff upon the axis of the stud 16 is in a plane at right angles to that of the 85 lower end of the standard, so that when the standard is clamped in place upon the fender of a vehicle upon a lateral incline, the flag staff may be adjusted so as to be held in erect position.

In using the invention, the lever 12 is turned downwardly so as to permit the jaw 6 to move to open position, and the jaw is then hooked under the flange of the vehicle fender (not shown) so that the flange extends between the jaw 6 and cushion 15, and the standard is then clamped in place by turning the lever 12 to its uppermost position, whereupon, the standard is held firmly in place upon the fender. The spring tongue 9 is then pressed inwardly which causes the stud to project through the opening 20 in the bar sufficiently to permit the insertion of the flag staff 19 through its perforated end. 15 Upon releasing the pressure applied to the tongue the flag staff is clamped against the outer face of the bar and thereby held seated in one or the other of the notches 24 of the rib 23, accordingly as adjusted.

20 By this construction the standard may be expeditiously clamped in place upon or removed from the vehicle, and the flag staff may be quickly applied and adjusted in connection with the standard, with but slight 25 effort upon the part of the attendant. Also, the device may be repeatedly applied, removed, and carried about without liability of loss of any of its various parts.

The yoke 10 is held from becoming displaced vertically upon the standard by the indentation 5 by which upward play of the yoke is limited, and from downward play by the loop 2. The stud 16 being permanently swiveled in connection with the spring tongue 9 is thereby held from becoming detached from the appliance, and thus the securing means for the attachment of the flag staff to the standard and also the clamping means for securing the standard to the vehicle may be easily operated without the use of a tool or the tightening and loosening of such means as screws or nuts, which means ordinarily are subject to depreciation because of wear from frequent use.

45 Claims:

1. A flag staff holder having a standard made of a flat steel bar, the lower end portion of which is upturned to form a spring loop and a movable jaw, and the upper end portion of which is downturned to form a spring tongue normally spaced from the adjacent portion of the bar, a portion of said bar between its ends having a quarter turn formed therein; a cushion disposed on said bar opposed to said jaw; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; a stop on the standard

for the lower end of said flag staff; and a projection on said standard having a series of notches for adjustably positioning the flag staff.

2. A flag staff holder having a standard made of a flat steel bar, the lower end portion of which is upturned to form a spring loop and a movable jaw, and the upper end portion of which is downturned to form a spring tongue normally spaced from the adjacent portion of the bar, a portion of said bar between its ends having a quarter turn formed therein; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; a stop on the standard for the lower end of said flag staff; and a projection on said standard having a series of notches for adjustably positioning the flag staff. 70 75 80 85 90

3. A flag staff holder having a standard made of a flat steel bar, the lower end portion of which is upturned to form a spring loop and a movable jaw, and the upper end portion of which is downturned to form a spring tongue normally spaced from the adjacent portion of the bar, a portion of said bar between its ends having a quarter turn formed therein; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; and a projection on said standard having a series of notches for adjustably positioning the flag staff. 95 100 105 110

4. A flag staff holder having a standard made of a flat steel bar, the lower end portion of which is upturned to form a spring loop and a movable jaw, and the upper end portion of which is downturned to form a spring tongue normally spaced from the adjacent portion of the bar, a portion of said bar between its ends having a quarter turn formed therein; a cushion disposed on said bar opposed to said jaw; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; a stop on the standard

staff against the standard when the tongue is released; and a stop on the standard for the lower end of said flag staff.

5. A flag staff holder having a standard made of a flat steel bar, the lower end portion of which is upturned to form a spring loop and a movable jaw, and the upper end portion of which is downturned to form a spring tongue normally spaced from the adjacent portion of the bar, a portion of said bar between its ends having a quarter turn formed therein; a cushion disposed on said bar opposed to said jaw; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; and a projection on said standard having a series of notches for adjustably positioning the flag staff.

6. A flag staff holder having a standard made of a flat steel bar, the lower end portion of which is upturned to form a spring loop and a movable jaw, and the upper end portion of which is downturned to form a spring tongue normally spaced from the adjacent portion of the bar; a cushion disposed on said bar opposed to said jaw; a clamping means consisting of a yoke and a lever provided with a cam pivoted in said yoke, disposed on the lower part of said standard for actuating said jaw; a perforated lug swiveled to said tongue and extending through an opening in the adjacent portion of the standard and adapted for the reception of a flag staff when the spring is depressed and to clamp said flag staff against the standard when the tongue is released; and a projection on said standard having a series of notches for adjustably positioning the flag staff.

7. A flag staff holder having a standard made of a flat steel bar, the lower end portion of which is upturned to form a spring loop and a movable jaw, and the upper end portion of which is downturned to form a spring tongue normally spaced from the adjacent portion of the bar; a clamping means consisting of a yoke and a lever provided with a cam pivoted in said yoke, disposed on the lower part of said standard for actuating said jaw; and a perforated lug swiveled to said tongue and extending through an opening in the adjacent portion of the standard and adapted for the reception of a flag staff when the spring is depressed and to clamp said flag staff against the standard when the tongue is released.

8. A flag staff holder comprising a standard having clamping means at its lower end for the attachment thereof to a vehicle body,

the upper end portion of said standard having a spring tongue in connection therewith the movable end of which is normally spaced from the adjacent face of the standard; and a perforated lug swiveled to said tongue and extending through an opening in said standard and adapted to receive a flag staff when the spring is depressed and to clamp said flag staff against the standard when the tongue is released.

In testimony whereof I affix my signature.
